UNITED STATES PATENT OFFICE.

LESLIE BOWN TAYLOR, OF BIRMINGHAM, ENGLAND.

PROJECTILE.

Application filed August 24, 1921. Serial No. 494,840.

To all whom it may concern:

Be it known that I, LESLIE BOWN TAYLOR, a subject of the King of Great Britain, residing at Grange Road, Bournbrook, 5 Birmingham, in the county of Warwick, England, have invented certain new and useful Improvements in or Relating to Projectiles, of which the following is a specification.

10 The said invention relates to the construction of projectiles for ordnance and small arms and in order that the said invention may be the better understood I remark that heretofore in the construction of 15 such bodies the location of the centre of inertia or centroid in relation to the length of axis and radius of gyration of the body has been more or less left to chance or arbitrarily fixed with the result that the 20 kinetic energy developed by a given impulse has not been conserved but on the contrary has been dissipated owing to premature and exaggerated precessional disturbances induced by or resulting from and 25 varying with the amount of error in the location of the centroid having regard to the length of axis and radius of gyration of the body.

The object of the said invention is to 30 eliminate wholly or in great part precessional aberrations in projectiles due to the cause hereinbefore referred to and further to establish a norm or standard by the application of which to the construction of 35 such bodies there results an optimum of efficiency due to the elimination wholly or in great part of the said precessional aberrations.

The underlying principles of my invention and their practical application to projectile construction as hereinafter fully described with reference to the accompanying drawings have been determined by experiment and a consideration of the following 45 mathematical propositions involved, namely:—

1. Maximum gyroscopic stability or equilibrium exists in a rotating rigid body when the axis of rotation is without precession.
- 50 2. The precession induced or developed in a rotating rigid body by a force acting to turn the axis at an angle to its normal or initial plane of rotation will be directed at

an angle to the said plane whose versed sine is commensurate to the force applied, and 55 will readily come under control in proportion as this versed sine is small.

Proposition 1 is axiomatic and proposition 2 will be evident from a consideration of the diagrams Figures 1 and 2 of the 60 drawings.

Fig. 1 is a diagrammatic view illustrative of the first of the above propositions.

Fig. 2 is a diagrammatic view illustrative of the second of the above propositions. 65

Fig. 3 is a diagrammatic view applying the principle of my invention to a shell and illustrating the cone of restitution and the radius of restitution relative thereto.

Figs. 4 and 5 illustrate diagrammatically 70 two projectiles, the cylindrical portions of which are identical and the mass equal but having different noses.

Fig. 6 illustrates diagrammatically one form of shell having a hollow nose or cap 75 applied thereto and shows the concavity in the cylindrical portion to compensate for the weight of the nose or cap.

Fig. 7 is a somewhat different construction showing diagrammatically the 80 assembling of the cap or nose, upon the cylindrical portion of the shell by means of a ring.

Fig. 8 shows rifling ridges adapted to co-operate with corresponding rifling grooves 85 of a shell.

Dealing with the first part of this proposition and referring to Figure 1, A represents a rotating rigid body the normal or initial axis of rotation of which is denoted 90 by the letters x, y .

x^1, y^1 denotes the plane of the said axis due to precession induced by a force of say m lbs. and x^2, y^2 the plane of the said axis due to precession induced by a force of 95 say n lbs.

Let o denote the point of intersection of the precessing axes x^1, y^1 and x^2, y^2 with the normal axis x, y and with the centre O and radius equal to axis o, y describe 100 the arc a, b cutting x^1, y^1 and x^2, y^2 at y^1 and y^2 respectively and thus fixing the extremities of the said axes.

By now dropping the lines y^1, y^3 and y^2 105 y^4 from the points y^1 and y^2 respectively and perpendicular to x, y and joining the

points y^3 and y^4 at which they intersect the arc a, b to the point o we complete figures (sections on the vertical axes) of the cones generated by the precessing axes a ,

- 5 y^1 and o, y^2 and further we are provided with triangles of reference $y^1 o c$ and $y^2 o d$ the versed sines y, c and y, d of which are commensurate with the forces which, from the hypothesis, determined the angles

0 $y^1 o c$ and $y^2 o d$.

The second part of the proposition will be demonstrated with reference to the diagram Figure 2 of the drawings.

In the said diagram the body outlined in 5 heavy lines may represent a top or more appropriately to the subject matter of the present specification a missile gyrating on its point or nose.

10 G is the centre of mass or inertia; P , P the plane of gyration; A, B the axis of gyration and b is the point or nose of the body or missile when the same has a short taper or conical front end. b^1 is the point or nose of the said body when the same 25 has a taper or conical front part or end (indicated in heavy dotted lines in the diagram) the axis of which is three times that of the short cone just referred to.

15 If x, x represents the plane on which the point b is contacting when the body is rotating with its axis normal to the said plane x, x that is to say, when there is no precessional aberration in the body, and x^1, x^1 denote the plane of the circle of precession when, under the effect of precessional aberration the axis occupies the inclined position indicated by the dotted lines b^2, b^3 b^2, b^3 then the distance between the said planes x, x and x^1, x^1 denoted by the letter o in the diagram, measures the vertical displacement of the centre of gravity G , due to precession, and the product of the said distance o into the mass or weight M of the body is the measure of the work 45 which would have to be performed to restore the body to its normal or vertical condition.

20 Now taking the body having the same cylindrical portion as the first body, but with the conical front end represented in heavy dotted lines, the axis of the said conical part being as before stated three times the length of the axis of the conical part of the first considered body. This second 55 body is presumed to be the same weight or mass M as the first body and by construction its centre of gravity is maintained at the point G .

25 Let y, y represent the plane with which the point b^1 is contacting when the body is rotating normally and y^1, y^1 the plane of the circle of precession of the point b^1 which circle is taken for comparative argument as equal to the circle of precession of the point b of the first considered body then

the distance between the planes y, y and y^1, y^1 indicated by o^1 in the diagram, measures the vertical displacement of the centre of inertia G in this second case and the product of the distance o^1 into M , the mass or weight of the body is, as before, the measure of the work which would require to be performed to restore this body to its normal or vertical position.

30 The distances o and o^1 are the versed sines of the respective angles of precession θ and ϕ and are in fact comparable with d, y and c, y respectively in the first diagram of reference Figure 1, therefore the second part of proposition 2 is demonstrated.

35 Further from the above I deduce the corollary that the products M^*O and M^*O^1 are measures of the energy dissipated owing to precessional aberration when the distance of the centre G to the point has the respective lengths $G b$ and $G b^1$ the circle of precession of the points b, b^1 being in each case equal.

40 To illustrate the manner in which I apply the above mathematical principles to provide a standard or norm for use in projectile construction—and also to define certain terms of reference, I have represented in Figure 3 a longitudinal section through the axis of a bullet having a cylindrical rear part and hollow conical front part or nose: $A B C D$ being the section of the cylindrical part and $C D b$ being the outline of the outer surface of the hollow conical cap or nose.

45 b, b^1 is the axis of the bullet and G is the centre of the rectangular middle plane or section of the cylindrical part. a^1 and b^2 denote the centres of inertia or points at which the mass may be deemed to be concentrated on either side of the axis b . b^1 when the projectile is rotating about the said axis; Ga^1 and Gb^2 being therefore radii of gyration denoted for convenience of reference hereafter by the symbol " R_1 " in the said Figure 3. The points a^1 and b^2 in the practical construction of a missile are determined as hereinafter described and to the dimension $a^1 b^2$ that is $2R_1$ I hereinafter apply the term "dynamic calibre."

50 By joining a^1 and b^2 to the extremity b of the axis b, b^1 I obtain the dotted conical figure a^1, b, b^2 .

55 To this conical figure I propose to apply the term "cone of restitution" and to the axis $G b$ of the said cone denoted in the said Figure 3 by the symbol " R_2 " the term "radius of restitution."

60 To the ratio

$$\frac{R_1}{2R_2}$$

65 I apply the term "dynamic ratio" and would point out that this ratio should not be confused with the customary ratio of calibres

to length of ogival head in projectile structure.

The radii R_1 and R_2 enable me to arrive at the angle of cone of restitution whose 5 versed sine must remain infinitesimal if I am to preserve an optimum of momentum in the projectile.

In the diagram Figure 3 I have represented the cylindrical portion of the projectile, the diameter of which is determined 10 by the calibre, as equal in length to two dynamic calibres which length I deem as the results of my experiments the preferable length of the said cylindrical part.

15 The points a^1 and b^2 which determine the dynamic calibre are ascertained as follows: I take a cylinder of the requisite material, calibre and weight of the complete projectile to be constructed and by well-established 20 mathematical rules and calculations find the centres of inertia for the same when rotating about its axis.

These points determine the dimension of 25 the base of the cone of restitution or factor $2R_2$ of the formula

$$\frac{R_1}{2R_2}$$

30 which I have defined as the dynamic ratio. I maintain the centre of gravity of the missile at the centre of figure of the cylindrical part A, B, C, D, that is to say, I definitely locate the plane of gyration of the mass at the middle cross sectional plane of 35 the said cylindrical part.

The base of the cone of restitution is thus fixed and also one extremity of the radius of restitution or factor R_1 . In order to maintain the centre of gravity G of the 40 mass of the complete projectile at the centre of the cylindrical part of the projectile when the hollow conical cap or nose is applied to the front end of the said cylindrical part I hollow out the said front end as illustrated by Fig. 6 to an extent proper to compensate for the weight of the said cap or nose.

Or I may partially compensate the weight 45 of the conical cap or nose by giving a convex or curved form to the base of the projectile as shown in Figure 3 the additional weight thus added to the base half of the cylindrical part proportionately reducing the extent to which the front or nose end of 55 the said cylindrical part is hollowed out. The radius of curvature of the base may be struck from the point of the bullet but in the case of a sabot carrying shell the radius of curvature is preferably struck 60 from the centre of gravity of the bullet.

In Figures 4 and 5 I give examples of two projectiles, shown in outline, the cylindrical portions of which are identical and the mass assumed to be equal.

65 Figure 4 has a radius of restitution equal

to three dynamic calibres and Figure 5 a radius of restitution equal to five dynamic calibres. The cones of restitution in the said figures are indicated by heavy dotted lines and in fine dotted lines I have indicated the outlines of the cones generated by the radii of restitution of the respective missiles assuming for the purpose of comparison that the diameters of the circles of precession of the respective noses of the 70 missiles are equal to the dynamic ratio which is the same in each case. Therefore the versed sines of the angles of the cones of restitution will respectively have the same proportion to each other as the versed sines of 75 the angle of the respective cones of precession and this ratio or proportion would be maintained whatever the angle of precession of the missiles.

It has already been demonstrated with 80 reference to Figures 1 and 2 that the smaller the versed sine of the angle of precession to the axes of rotation the more readily will the precession come under control and also the less will be the dissipation of the gyroscopic energy of the body.

85 It therefore follows that the missile Figure 5 has superior gyroscopic momentum and stability to the missile of Figure 4 the 90 superiority arising from the increased length of the radius of restitution R_1 which gives a higher value to the dynamic ratio.

$$\frac{R_1}{2R_2}$$

100 The cones of restitution constitute figures of merit or graphical representations indicative of the gyro-stability of the missiles, and a further advantage which attends the obtaining of the said cones of restitution is 105 that the inclination of the sides of the said cones provides me with the most desirable angle or pitch for the rifling of the barrels of fire-arms to be constructed for the discharge of the said projectiles. I have found 110 that where the said angle or pitch is made equal to the angle of restitution the ranging power or ability of the missile to maintain the "nose on" direction from the muzzle to the target, is a maximum when the 115 rifling has a length equal to one half turn or at most to a complete turn. The rifling is formed at the muzzle end or preferably at the breech end of the barrel and the interior of the barrel beyond the rifling is left 120 with a smooth bore.

By assigning a predetermined value to the dynamic ratio

$$\frac{R_1}{2R_2}$$

125 projectiles having definite and characteristic ballistic properties will be obtained.

In column 1 of the following table, headed "Table of comparative values", we assign 130

predetermined values to the axial length of the cone of restitution or dynamic ratio

$$\frac{R_1}{2R_2}$$

and in columns 2, 3 and 4 is given opposite each of the said predetermined ratios the data noted at the head of the respective columns and resulting from the assigned or predetermined value of the said dynamic ratio.

Table of comparative values.

1 Dynamic ratio. $\frac{R_1}{2R_2}$	2 Angle of cone of restitution (also preferred pitch of rifling).	3 Versed sine $\times 100$ (index of percentage of energy dissipated)	4 Cosine $\times 100$ (index of percentage of energy available).
	Degrees.		
1	25.34	9.80	90.20
1½	18.26	5.13	94.87
2	14.2	2.98	97.02
2½	11.19	1.85	98.15
3	9.28	1.36	98.61
3½	8.8	1.00	99.00
4	7.8	0.77	99.23
4½	6.21	0.61	99.39
5	5.43	0.50	99.50
5½	5.13	0.41	99.59
6	4.46	0.35	99.65
6½	4.24	0.29	99.71
7	4.5	0.25	99.75
7½	3.49	0.22	99.78
8	3.35	0.20	99.80
8½	3.22	0.17	99.83
9	3.11	0.15	99.85
9½	3.0	0.14	99.86
10	2.52	0.13	99.87

A reference to column 2 of the above table shows at a glance the preferred angle of pitch of the rifling for a projectile when its dynamic ratio has been determined and reference to columns 3 and 4 gives the percentage of energy which will be dissipated and the percentage of the terminal or available energy, the one being complementary of the other.

It will be noted that the original shape of the front end or cap of the missiles represented in no way affects the factors governing the method of construction hereinbefore described and the properties conferred thereby on the missile and I wish it to be understood that the said front end or cap may be otherwise shaped than truly conical, for example, the said cap or front part may have what is technically termed an "ogival" shape.

Preferably the said front end or cap is connected to the rear or cylindrical part of the projectile by a screwed ring — ε — as is illustrated in Fig. 7, which ring may constitute the driving or steady band or one of the driving or steady bands of the projectile, and the cylindrical part of the projectile may be and preferably is provided

on its exterior surface by casting or otherwise with a series of ribs or feathers shown diagrammatically in Fig. 8 and marked ε' , the said ribs or feathers having an inclination to the plane of the axis equal to the inclination of the sides of the cone of restitution and angle of the pitch of the rifling or in other words the said ribs or feathers fit into the rifling grooves of the barrel when the said grooves have the preferred inclination.

By the improvements hereinbefore described I have found that a projectile when fired from a small arm or piece of ordnance receives and conserves an optimum of gyrostatic momentum and maintains throughout its flight its angle of departure, thereby avoiding the destructive precessional aberrations which obtain in an ordinary projectile due to constant change of the axis of gyration from that at which it left the muzzle of the fire-arm. By reason of the planing phenomenon asserting itself throughout the descending portion of the trajectory the projectile will strike the ground on the edge of its base its axis preserving the same or approximately the same direction as that which it had when it left the fire-arm.

I claim—

1. A bullet or projectile having a cylindrical portion and so constructed that its plane of gyration is preserved at the axial center of the cylindrical portion of the said projectile and having a "cone of restitution," the axis of which is equal to at least three "dynamic calibres," of the projectile.

2. A bullet or projectile having a cylindrical and a tapered portion, said cylindrical portion having a length equal or approximately equal to two dynamic calibres and in which the centre of mass or centroid of the projectile is preserved at the axial centre of the said cylindrical part.

3. A bullet or projectile having a cylindrical and a tapered portion, said cylindrical portion having a length equal or approximately equal to two dynamic calibres and in which the centre of mass or centroid of the projectile is preserved at the axial centre of the said cylindrical part by hollowing out the said cylindrical part at the end to which the nose is applied, the portion of the axis of the bullet or projectile from the middle of the cylindrical part to the tip of the tapered portion having a length equal to at least three times the dynamic calibre of the missile.

In testimony whereof I have hereunto set my hand.

LESLIE BOWN TAYLOR.
